SMOKING PIPE

Clarence L. Carter, Pittsburgh, Pa.

Application February 12, 1935, Serial No. 6,159

9 Claims. (Cl. 131—12)

This invention relates to a pipe for smoking tobacco and more particularly to a pipe of the up-draft type.

An object of the invention is to provide a pipe of this character having superior smoking qualities which is simple and sturdy of construction, economical to manufacture, and both light of weight and pleasing to the eye.

Another object is to provide a pipe which is productive of a cool dry smoke and in which the most economically feasible consumption of tobacco is obtained.

A further object is to provide a pipe which is adapted to prevent any ashes or fire being dropped from it while it is being used. This particularly adapts it for use in the home and in the automobile where the type of pipe customarily used in the past has been the cause of considerable trouble and damage due to the ashes falling out of them, such for example as the damaging of the user's clothes, starting of fires, wrecking of automobiles and sometimes even homes, although in the latter case not necessarily because of fires.

An additional and exceptionally desired feature of the invention is the provision of a pipe having a totally enclosed bowl and one free of any distasteful smoking such as is customarily encountered in the common form of pipe when the fire reaches the bottom of the bowl.

These and various other objects as well as the various other novel features and advantages of the invention will be apparent when the following detailed description is read in conjunction with the accompanying drawing of which Fig. 1 is a side view of a pipe made in accordance with the invention; Fig. 2 a sectional view of the same; Fig. 3 a view similar to Fig. 2 of a modification of the invention; Fig. 4 an exploded sectional view of the bowl encasing shell; Fig. 5 a top view; Fig. 6 a detail sectional view of the snap connection between the two parts of the bowl encasing shell; Fig. 7 a plan view of the grid used for holding the tobacco in the bowl; and Fig. 8 a perspective view of a pellet of tobacco adapted for use in the modification of the invention shown in Fig. 3.

Referring in detail to the drawings according to this invention a pipe is provided which comprises an inverted bowl 1 having a duct 2 in it communicating with the inner end of the tobacco chamber 3 and in which a conventional stem 4 provided with the usual mouth-piece is secured by a suitable coupling 5.

For totally encasing such bowl so as to pre-

vent any ashes or sparks falling from it a shell or housing is provided comprising an upper part 6 and a lower part 7 which may be made of any suitable material, but shown here as being made of metal. As illustrated the upper of these parts forms a support for the lower one and is itself held in place by the connection of the stem to the bowl, the bowl being provided with a short stub stem 8 for spacing the shell from the side walls of the bowl proper so as to provide a heat insulating and air circulating space between the bowl and shell.

In the top of the upper shell part 6 there is provided a series of holes or vents 9 through which the air is drawn into the pipe when it is smoked and which, as will be apparent, passes downwardly around the bowl and then upwardly through the tobacco or fire chamber and into the user's mouth by way of the stem 4. In accordance with such provision the incoming air is made not only readily available for supporting the combustion of the tobacco but also functions to cool the side of the bowl.

To facilitate the filling, lighting and emptying of the pipe, the lower section 7 of the bowl encasing shell is connected to the upper section 6 in such way that it can be readily removed but at the same time so that it will be firmly held in place when attached to it. While various means may be employed for this purpose such is accomplished in the disclosed embodiment of the invention by the means shown best in Fig. 6. In accordance with such construction the lower end of the upper shell part 6 is crimped inwardly to provide it with a shallow retaining groove 11. In this there is mounted a small expandible or split wire ring 12. The upper edge of the lower shell part 7 is in turn crimped inwardly to provide a curved upwardly disposed but outwardly projecting lip 13 which is of slightly greater outside diameter than the inside diameter of the ring 12 but sufficiently yieldable to permit its being snapped into the ring supported by the crimped edge 11 of the upper shell. By such a connection the lower shell part 7 can be easily snapped into the upper one and removed by a relatively small force and at the same time be firmly held in place when connected.

Since the outer shell does not in any way come in contact with the burning tobacco or any appreciable amount of the smoke produced thereby which is drawn into the mouth it may, as previously stated, be made of any kind of material desired. However, as it is desirable to make the pipe as light as possible it is preferably made

of some very light material which has sufficient strength to be capable of withstanding rough usage such as a pipe frequently encounters. For these reasons some such material as a strong 5 aluminum alloy or the like is recommended and the outer surface thereof is treated with any suitable coating to give the pipe a pleasing appearance. It may of course also be made in various attractive shapes.

10 It will also be appreciated that inasmuch as the bowl 1 is protected as it is by the shell and maintained at a low temperature by the air drawn through the pipe it can be made relatively light to further reduce the weight of the pipe.

15 In addition by attaching the shell and stem to the bowl in the manner described a number of bowls can be interchangeably used in each shell whereby through the provision of a plurality of bowls the user has the equivalent of a plurality 20 of pipes in so far as smoking qualities are concerned and obviously these bowls can be made of various materials such as brier, meerschaum, plain wood, clay, corn-cob, or any other suitable material.

25 As a further feature of the invention a grid 14 is provided to firmly hold the tobacco in place in the bowl as it is consumed. While such an element as will be apparent may take various forms it is here illustrated as being made of 30 spring steel wire and formed substantially in the shape of a pancake coil having an outer diameter slightly less than the inner diameter of the tobacco chamber and a centrally elongated portion 14a by means of which it is yieldably urged 35 into the bowl. When used it is mounted in the lower shell with its flat portion disposed in the tobacco chamber. For retaining it in place a mushroom shaped boss 15 is provided in the base of the lower shell part 7 and the lower end of the 40 spring 14a so formed as to be snapped onto or otherwise secured to this boss.

In the modification of the invention illustrated in Fig. 3 a bowl is provided which comprises a base portion 1a and a porous wall portion 16, the 45 latter being mounted in a groove 17 cut in the lower end of the base 1a. In such form of the invention it is contemplated that tobacco rolled in pellets like cigarettes as shown in Fig. 8 will be used. Hence a solid bowl wall is not required, 50 permitting the use of a wire gauze or the like for the wall portion of the bowl whereby the weight of the pipe is further reduced. To retain the pellets 18 in the bowl the lower portion of the chamber in the base 1a is tapered slightly at 19 55 to grip the upper end of the pellet when pressed into it.

In this latter form of the pipe, which is intended more particularly for use as a lady's pipe, the grid 14 may also be used as well as in the 60 previously discussed type although it may be dispensed with in both forms if desired and the pipe satisfactorily used.

In addition a porous mat or absorbent 20 may be mounted in the top of the shell between it and 65 the upper face of the bowl 1 and treated with rum or some other flavoring medium to enhance the quality of the smoke in accordance with the invention.

In using such a pipe the lower shell part 7 is re- 70 moved when it is desired to load it and the pipe then lit in the customary manner. As soon as it is lit the lower shell part 7 is snapped in place and the pipe turned to its correct position for smoking. When so assembled there is no possi- 75 bility of the tobacco or ashes in the pipe falling

out nor can the tobacco in it be forcibly burned as frequently takes place when the common form of pipe is smoked in a strong wind or while riding in an automobile.

Furthermore, in such a pipe there is but slight, 5 if any, tendency for moisture to collect in it which makes for a cool dry smoke. In addition, since the tobacco in the inner end of the fire chamber does not become moist, it can be practically completely used, and with no distasteful 10 smoking such as is encountered when the fire tends to eat into the heel of the load in a common form of pipe.

According to the provisions of the patent statutes, I have explained the principle and construction of my invention and have illustrated and described what I now consider to represent its best embodiment. However, I desire to have it understood that, within the scope of the appended claims, the invention may be practiced 15 otherwise than as specifically illustrated and described.

I claim:

1. A smoking pipe comprising an inverted bowl provided with a stub stem at its upper end, 25 a hollow stem provided with a mouth-piece secured to said stub stem and a shankless shell substantially completely encasing said bowl except for a draft vent therein and held in place solely by the engagement of said hollow stem with 30 said stub stem.

2. A smoking pipe comprising an inverted bowl, a hollow stem provided with a mouth-piece mounted to communicate directly with the inner end of and directly attached to a wall of said bowl, a shankless casing substantially totally enclosing said bowl except for a draft vent in the end thereof opposite the lighting end of the bowl and mounted in spaced relation to the walls thereof, the bowl being held in place in said casing 35 solely by said hollow stem.

3. A smoking pipe comprising an inverted bowl, a hollow stem provided with a mouth-piece mounted to communicate directly with the inner end of and directly attached to the wall of 45 said bowl, a shell formed in two sections substantially completely encasing said bowl except for a draft vent in the end thereof opposite the lighting end of the bowl, and retaining means for detachably holding the sections of said shell in assembled relation, said hollow stem being the sole support for the bowl in said shell.

4. A smoking pipe comprising an inverted bowl, a shankless hollow shell consisting of an upper and lower section disposed to encase said bowl and provided with draft vents in its upper end, means for suspending said bowl in said shell, a stem communicating directly with and connected directly to the inner end of said bowl, and retaining means for detachably connecting the lower to the upper section of said shell to permit loading and unloading of the bowl, said stem being the sole support for the bowl in the shell.

5. A smoking pipe comprising an inverted bowl provided on its exterior with an integral short stub stem having a duct therein communicating with the inner end of the tobacco chamber in said bowl, a hollow stem provided with a mouth-piece secured to said stub stem, and a casing substantially totally surrounding said bowl except for a draft vent therein and secured to said bowl by said hollow stem with the side walls of the casing spaced from the sides of said bowl and held in such position by said stems only.

6. A smoking pipe comprising an inverted bowl, a two part thin shankless metal shell vented at its upper end enclosing said bowl and spaced from the ends and sides thereof, means for suspending said bowl at one point only in said shell, a hollow stem provided with a mouth-piece arranged to communicate directly with and connected directly to the inner end of the tobacco chamber in said bowl, and retaining means for 10 detachably connecting the lower to the upper part of said shell.

7. A smoking pipe comprising an inverted bowl, a shankless cylindrical shell divided into two parts between its ends encasing said bowl and 15 vented at its upper end, means for suspending said bowl at one point only in said upper shell

portion, a hollow stem extending through said shell and connected to said bowl, and means for detachably connecting the lower part of said shell to the upper part.

8. A smoking pipe according to claim 2 provided with a porous mat for receiving a volatile flavoring disposed in the path of the air flow between the vent in the shell and the inlet to the bowl. 5

9. A smoking pipe according to claim 2 in which 10 the vents are located in the top of the encasing shell having a porous flavoring receiving mat arranged between the top of the shell and the upper end of the bowl.
